RADIO CABINET

Arthur T. Murray, Springfield, Mass., assignor to
 United American Bosch Corporation, Springfield, Mass., a corporation of New York

Application December 23, 1933, Serial No. 703,765

2 Claims. (Cl. 250—14)

The invention relates to radio cabinets, and particularly to those having means for permanently supporting a radio chassis in an inclined position therein in such manner that the dials and other controls can be readily observed and actuated by the user from either a standing or sitting posture.

Heretofore in such cabinets the receiver has usually been mounted flat, the controls being arranged on a vertical surface. While such controls can be reached, one cannot easily observe them without sitting or stooping, unless of course the cabinet is placed upon an elevated support.

In this invention I provide such construction that the controls can be seen and actuated both from the front and above the cabinet, in any of the usual positions thereof, without the operator assuming any other than an upright bodily position or a sitting position, as desired. For this purpose the receiver chassis is fixed on a slant in the cabinet and the controls are disposed on a panel that is inclined in such way that they can be readily connected to the movable parts of the chassis. Preferably the cabinet has a folding or sliding member to cover the controls when the set is not in use.

The objects and advantages of the invention are clearly set forth in the following description taken with the drawing which shows several embodiments thereof, but I reserve the right to make changes in details not shown herein but nevertheless falling within the spirit and scope of the invention.

On the drawing:

Fig. 1 is a perspective view of a cabinet according to my invention showing the controls in exposed position; Fig. 2 shows the top of said cabinet with cover closed; Fig. 3 is a vertical section from front to rear through the middle of Fig. 1, illustrating the receiver chassis held in slanting or inclined position in the cabinet; and Figs. 4 and 5 are similar sections showing modifications. On the drawings the same numerals identify the same parts throughout.

The cabinet 1 has adjacent its top, a panel 2 which slopes down from back to front. This panel may be in depressed position or inset with respect to the top and front of the cabinet, between a pair of triangular members 3 at the two sides. The panel has a tuning knob 4 on a shaft extending through it, and has an opening at 5 through which the dial or scale is observable. The panel may also carry additional controls such as knobs or arms 6 for operating other devices inside the cabinet such as switches, volume control,

tone control, etc. The controls 4 and 6 are thus mounted adjacent the top 7 of the cabinet, but as the panel 2 is inclined, they can easily be seen from the front of the cabinet 1 or from above it, and can be conveniently manipulated, whether the user stands or sits and whether the cabinet stands on the floor or on a support of ordinary height.

I provide a cover for the panel 2 consisting of a pair of sections 8 and 9, the former being hinged at 10 adjacent the upper edge of the panel 2 and the latter hingedly connected to the former and carrying a knob 11. Along the front or lower edge of the panel is a narrow horizontal surface 12 on which the lower edge of the panel section 9 can rest when the cover is drawn down over the panel 2. The front of the cabinet has an opening 13 adjacent a loud speaker inside. When the cover is closed, top 7 is flat and the cabinet is continuous as shown in Fig. 2. When the receiver is to be used, the cover 8, 9 is raised and folded back to rest upon the top 7 as shown in Fig. 1, or against an object standing on the rear part of the top.

To enable the controls to be disposed in conjunction with the sloping panel 2, the chassis 14 of the receiver is fixed at a corresponding incline in the cabinet 1. Thus the chassis 14 is mounted inside the cabinet on a slanting base or support 15 supported by triangular projections 16 secured to the inner face of the front of the cabinet, as shown in Fig. 3. These triangular projections may be adjacent each side of the cabinet, and the chassis 14 bearing all the necessary parts of the receiver is permanently secured to support 15. The shafts which are actuated by the knobs 4 and 6 extend through the panel 2 into the receiver. The base 15 and panel 2 are hence substantially perpendicular to each other. As illustrated in Fig. 3 the loud speaker 17 can be secured to the front of the cabinet 1 around the edges of the opening 13. The speaker is thus secured adjacent a highly damped section of the cabinet front wall. Vibrations therein are greatly reduced and are correspondingly lessened in the side walls and receiver chassis. An improved baffle is formed for the speaker and tube microphonics are eliminated in general.

In Fig. 4 the loud speaker is mounted upon an apertured vertical support 18 which may be affixed to the lower edge of the base 15 and to the bottom of the cabinet a short space behind the opening 13.

In Fig. 5 the cover is made up of the sections 8' and 9', the connected edges of which are hinged. The main section 8' is not hinged to the cabinet 55

but rests, when the cover is in closed position, on the top of a guide 19 at the rear of the chassis. This guide is parallel with another guide 20, and the two are joined at the bottom to form a pocket into which the cover can be pushed to expose the control panel 2. The cover can be withdrawn by pulling on the knob 11 and moved into position over the panel 2, suitable stops (not shown) being carried by the section 8' to engage projections at the top of the guides 19 and 20 to limit the movement of the cover. The base 15' is extended at a slant towards the bottom of the cabinet and on the rear face thereof the speaker 17 is attached around the opening 21.

As shown in Figs. 3 and 4, the top 7 of the cabinet has a depending element or strip 20 to support the rear end of the sloping panel 2, the forward end being affixed in any suitable manner to the front of the cabinet 1. In Fig. 5, the rear edge of the panel 2 may be secured to the guide member 19.

For the sake of clearness, the cover 8, 9 and the base 15 in Fig. 3, the panel 2, base 15, speaker 17 and member 18 in Fig. 4, and the base 15' and speaker 17 in Fig. 5 are shown in elevation. In Fig. 4, the tubes and other parts are omitted from the chassis 14.

It will be apparent that many changes and modifications may be made in this invention by any one skilled in the art without departing from the spirit and scope of the invention as defined by the following claims.

Having described the invention, what I claim is:

1. In a radio cabinet, a chassis support extending downwardly at an angle from the vertical, a receiver chassis mounted on said support, a control panel mounted in said cabinet adjacent said chassis and positioned at right angles to said support, brace means cooperating with an adjacent wall of said cabinet for maintaining said support in angular inclination, and a loud speaker mounted upon said support below said receiver chassis. 15

2. In a radio cabinet, an inclined control panel, a chassis support secured in said cabinet at substantially a right angle to said panel and inclining downwardly therefrom, a receiver chassis mounted on said support, brace means maintaining said support in angular inclination and directing the weight of said chassis and support against the front wall of said cabinet, and a loud speaker mounted in the lower front wall of said cabinet directly below said receiver chassis. 20

ARTHUR T. MURRAY. 25
